(57) **CLAIM**

The ornamental design for an bone hook plate, as shown and described.

DESCRIPTION

FIG. 1—Top, front perspective view of the first embodiment for a bone hook plate, showing our new design;

FIG. 2—Right side elevation view thereof;

FIG. 3—Left side elevation view thereof;

FIG. 4—Bottom plan view thereof;

FIG. 5—Top plan view thereof;

FIG. 6—Front perspective view thereof;

FIG. 7—Back side perspective view thereof;

FIG. 8—Top, front, right side perspective view of the second embodiment for a bone hook plate;

FIG. 9—Right side elevation view thereof;

FIG. 10—Left side view thereof;

FIG. 11—Bottom plan view thereof;

FIG. 12—Top plan view thereof;

FIG. 13—Front perspective view thereof; and,

FIG. 14—Back side perspective view thereof.
